UNITED STATES PATENT OFFICE.

GEORGE V. STRAHAN, OF NEWARK, NEW JERSEY, AND FREDERICK W. MATHIEU, OF NEW YORK, N. Y., ASSIGNORS TO MITCHELL VANCE CO., INC., OF NEW YORK, N. Y., A CORPORATION OF NEW YORK.

DESIGN FOR AN ORNAMENTAL RING FOR LIGHTING FIXTURES.

Application filed April 18, 1922. Serial No. 1,821. Term of patent 7 years.

To all whom it may concern:

Be it known that we, GEORGE V. STRAHAN and FREDERICK W. MATHIEU, citizens of the United States of America, and residents, respectively, of the city of Newark, county of Essex, and State of New Jersey, and of the borough of Manhattan, city, county, and State of New York, have invented a new, original, and ornamental Design for an Ornamental Ring for Lighting Fixtures, of which the following is a specification,

reference being had to the accompanying drawing, forming part thereof.

The single figure of the drawing is a plan view of an ornamental ring for a lighting fixture showing our new design.

We claim:

The ornamental design for an ornamental ring for lighting fixtures, as shown.

GEORGE V. STRAHAN.
FREDERICK W. MATHIEU.
